ABSTRACT OF THE DISCLOSURE

The present invention provides new aminopropanol derivatives of the formula:

wherein

R₁ is hydrogen, cycloalkyl of 3 to 7 carbon atoms, alkyl of 1 to 8 carbon atoms, cycloalkylalkyl, in which the cycloalkyl ring is of 3 to 7 carbon atoms and the alkyl residue is of 1 to 6 carbon atoms, or phenylalkyl or diphenylalkyl, in which the phenyl radicals may be substituted in the 3, 4 or 5 position by 1 to 3 hydroxy or methoxy groups, or in the 3,4 position by a methylenedioxy group, and in which the alkyl residue is of 1 to 6 carbon atoms,

and acid addition salts thereof.

Processes for the production thereof and intermediates therefor are also described.

The compounds exhibit broncholytic properties.

The present invention relates to aminopropanol derivatives.

In accordance with the invention there are provided new compounds of Formula I,

wherein

R₁ is hydrogen, cycloalkyl of 3 to 7 carbon atoms, alkyl of 1 to 8 carbon atoms, cycloalkylalkyl, in which the cycloalkyl ring is of 3 to 7 carbon atoms and the alkyl residue is of 1 to 6 carbon atoms, or phenylalkyl or diphenylalkyl, in which the phenyl radicals may be substituted in the 3, 4 or 5 position by 1 to 3 hydroxy or methoxy groups, or in the 3,4 position by a methylenedioxy group, and in which the alkyl residue is of 1 to 6 carbon atoms,

and acid addition salts thereof.

Further, in accordance with the invention a compound of Formula I may be obtained by a process comprising

(a) Converting the ether groups into hydroxy groups in a compound of Formula II,

wherein

R₁ is as defined above, and
R₂ is methyl, ethyl or benzyl,

2

to produce a compound of Formula Ia,

wherein

R₁^I is hydrogen, cycloalkyl of 3 to 7 carbon atoms, alkyl of 1 to 8 carbon atoms, cycloalkylalkyl, in which the cycloalkyl ring is of 3 to 7 carbon atoms and the alkyl residue is of 1 to 6 carbon atoms, or phenylalkyl or diphenylalkyl, in which the phenyl radicals may be substituted in the 3, 4 or 5 position by 1 to 3 hydroxy groups, and in which the alkyl residue is of 1 to 6 carbon atoms, or

(b) Hydrogenolytically debenzylating a compound of Formula III,

wherein

R₁^{II} is hydrogen, cycloalkyl of 3 to 7 carbon atoms, alkyl of 1 to 8 carbon atoms, cycloalkylalkyl, in which the cycloalkyl ring is of 3 to 7 carbon atoms and the alkyl residue is of 1 to 6 carbon atoms, or phenylalkyl or diphenylalkyl, in which the phenyl radicals may be substituted in the 3, 4 or 5 position by 1 to 3 hydroxy or methoxy groups, or in the 3,4 position by a methylenedioxy group, and are separated from the nitrogen atom by at least two carbon atoms, and in which the alkyl residue is of 2 to 6 carbon atoms,

R₃ is hydrogen or benzyl, and

R₄^I is benzyl or, when R₃ is benzyl, is hydrogen or benzyl, to produce a compound of Formula Ib,

wherein R₁^{II} is as defined above, or

(c) Reacting a compound of Formula IV,

wherein R₃ is as defined above,

with a compound of Formula V,

wherein

R₄ is hydrogen, alkyl of 1 to 7 carbon atoms, or cycloalkyl or cycloalkylalkyl, in which the cycloalkyl ring is of 3 to 7 carbon atoms and the alkyl residue is of 1 to 5 carbon atoms, or phenylalkyl or diphenylalkyl, in which the phenyl radicals may be substituted in the 3, 4 or 5 position by 1 to 3 hydroxy or methoxy groups, or in the 3,4 position by a methylenedioxy group, and are separated from the oxygen atom by at least two carbon atoms, and in which the alkyl residue is of 1 to 5 carbon atoms, and

R₅ is hydrogen or alkyl of 1 to 7 carbon atoms, or

R₄ and R₅ together with the carbon atom to which the oxygen atom is joined form a cycloalkyl group of 4 to 7 carbon atoms, provided that when R₅ is alkyl, when

R_4 is alkyl the total number of carbon atoms in R_4 and R_5 is not greater than 7, and when R_4 is cycloalkylalkyl, phenylalkyl or diphenylalkyl the total number of carbon atoms in R_5 and in the alkyl residue of R_4 is not greater than 5,

under reductive alkylation conditions, to produce a compound of Formula Ic,

wherein R_1''' is cycloalkyl of 4 to 7 carbon atoms, primary or secondary alkyl of 1 to 8 carbon atoms, cycloalkylalkyl, in which the cycloalkyl ring is of 3 to 7 carbon atoms and the alkyl residue is of 1 to 6 carbon atoms, or phenylalkyl or diphenylalkyl, in which the phenyl radicals may be substituted in the 3, 4 or 5 position by 1 to 3 hydroxy or methoxy groups, or in the 3,4 position by a methylenedioxy group, and are separated from the nitrogen atom by at least 2 carbon atoms, and in which the alkyl residue is of 2 to 6 carbon atoms, or

(d) Treating a compound of Formula VIId,

wherein

R_1 is as defined above, and each of R_6 and R_7 is alkyl of 1 to 4 carbon atoms,

with a metal hydride which will reduce an ester to an alcohol, and hydrolyzing the resulting reaction product, to produce a compound of Formula I; and, if desired, separating any resulting racemates of the compounds of Formula I into their optical antipodes and/or converting the resulting compounds of Formula I into their acid addition salts.

The alkyl groups represented by the symbols R_1 may be straight-chained or branched and preferably contain 1 to 4 carbon atoms; the cycloalkyl groups preferably contain 5 ring members. The alkyl residue of the aralkyl group may be straight-chained or branched and is preferably of 2 to 5 carbon atoms.

Process variants (a) may be effected in accordance with conventional methods for ether splitting. Thus, for example, a compound of Formula II may be allowed to react with a Lewis acid, e.g. boron tribromide or aluminium chloride, in an inert organic solvent, e.g. a halogenated hydrocarbon such as methylenechloride or carbon tetrachloride, or an aromatic hydrocarbon such as toluene or benzene, at -80 to +70°C., or a compound of Formula II may be treated for a short period with a strong mineral acid, e.g. hydrobromic or hydroiodic acid, optionally at an elevated temperature, e.g. at approximately 20 to 100°C., or a hydrochloride, hydrobromide or hydriodide of an organic base such as aniline or pyridine is allowed to act on a compound of Formula II at an elevated temperature, e.g. about 20 to 100°C. In this process any methoxy or methylenedioxy groups which are present in the substituent R_1 are also converted, so that a compound of Formula Ia is obtained.

The debenzylation in accordance with process variant (b) may, for example, be effected by catalytic hydrogenation in an inert solvent, e.g. ethyl acetate, or a lower alkanol such as methanol or ethanol. Hydrogenation is preferably effected at a temperature from 20 to 100°C., at a hydrogen pressure of 1 to 100 atmospheres. A palladium catalyst may, for example, be used as hydrogenation catalyst.

Process variant (c) may, for example, be effected by catalytic reduction with a platinum, palladium or nickel catalyst, at 1 to 100 atmospheres hydrogen pressure and at 20 to 80°C., in an inert solvent such as ethanol.

In process variant (d) the metal hydrides suitable for the reaction are, for example, optionally complex aluminium metal hydrides, such as lithium aluminium hydride, aluminium hydride, diisobutyl aluminium hydride, trialkoxy lithium aluminium hydrides, sodium dihydro-bis-(2-methoxyethoxy)aluminate, or dibroane or lithium borohydride, and the reaction is preferably effected at room temperature. Reaction times under preferred conditions are from approximately 1/2 to several hours.

10 The compounds of Formula I may be isolated from the reaction mixture in conventional manner.

When optically active starting materials are used, the processes of the invention yield optically active compounds of Formula I. When racemic compounds are used as starting materials, the processes of the invention yield 15 racemates of the compounds of Formula I, which, if desired, may be separated into the optical antipodes in conventional manner, e.g. by converting the racemates with optically active acids into a mixture of their diastereoisomeric salts, and isolating the optical antipodes of the 20 compounds of Formula I therefrom.

The compounds of Formula II may be obtained by a process comprising

(a) Reducing the ester group in a compound of Formula VIIa,

30 wherein R_1 , R_2 and R_6 are as defined above, or

(b) Reducing a compound of Formula VII,

35 wherein R_2 and R_6 are as defined above, to produce a compound of Formula IIa,

40 wherein R_2 is as defined above, or

(c) Reductively reacting a compound of Formula IIc,

45 wherein R_2 is methyl or ethyl,

50 and which is a special case of the compounds of Formula IIa, with a compound of Formula V, under the reaction conditions described in process (c), to produce a compound of Formula IIb,

55 wherein R_1''' and R_2 are as defined above.

Process variants (a) and (b) may, for example, be effected in an inert solvent, e.g. an ether such as diethyl ether, tetrahydrofuran, dioxane or dimethoxyethane, with lithium aluminium hydride or aluminium hydride.

60 Process variants (a) and (c) yield optically active compounds of Formula II when optically active compounds are used as starting materials. When racemic compounds are used as starting materials in both processes, as well as in process variants (b), racemates of compounds of Formula II are obtained, which may be separated into their optical antipodes in conventional manner, e.g. by converting racemates with optically active acids into a mixture of their diastereoisomeric salts, and isolating the optical antipodes of the compounds of Formula II therefrom.

Compounds of Formula IIIa,

wherein R_1^{II} is as defined above,

may, for example, be obtained by converting the ether groups into hydroxy groups in a compound of Formula VIII,

wherein R_1^{II} and R_2^I are as defined above, e.g. as described in process variant (a).

Compounds of Formula IIIb,

wherein R_1^{II} and R_3 are as defined above,

may, for example, be obtained by reducing a compound of Formula VIb,

wherein R_1^{II} , R_3 and R_6 are as defined above,

as described in process variant (β).

Compounds of Formula VIII may, for example, be obtained by reducing a compound of Formula VIc,

wherein R_1^{II} , R_2^I and R_6 are as defined above, as described in process variant (β).

The compound of Formula IVa

is a special case of the compounds of Formula I.

Compounds of Formula IVb,

wherein R_3 and R_3^I are as defined above,

are a special case of the compounds of Formula III.

Compounds of Formula VI,

wherein R_1 , R_2 , R_3 and R_6 are as defined above, may, for example, be obtained by addition of a compound of Formula X,

wherein R_1 and R_3 are as defined above, to a compound of Formula IX,

wherein R_2 and R_6 are as defined above.

The reaction may, for example, be effected at 20 to 100° C., using equimolar amounts of both compounds, and optionally in an inert solvent, e.g. a lower alcohol.

Compounds of Formula VIId may, for example, be obtained by reacting a compound of Formula IXa,

wherein R_6 and R_7 are as defined above,

with a compound of Formula Xa,

wherein R_1 is as defined above,

in accordance with the process described for the production of compounds of Formula VI.

Insofar as the production of the starting materials is not particularly described, these are known or may be produced in accordance with known processes, or in a manner analogous to the processes described herein or to known processes.

The compounds of Formula I are useful because they possess pharmacological activity in animals. In particular, the compounds are useful in the treatment of bronchospasms, such as in bronchial asthma, as indicated by their exhibition of generalized sympathomimetic, especially broncholytic, properties, as illustrated by their effect in vagally induced bronchospasms, and bronchospasms produced by histamine and acetylcholine in cats and guinea pigs.

For the above-mentioned use, the dosage administered will, of course, vary depending on the compound employed, mode of administration and treatment desired. However, in general satisfactory results are obtained when administered at a daily dosage of from about 0.005

to 5 mg./kg. animal body weight, conveniently given in divided doses 2 to 3 times a day, or in sustained release form. For the larger mammals the total daily dosage is in the range of from about 10 to 20 mg., and dosage forms suitable for oral administration comprise from about 3 to 10 mg. of the compound admixed with a solid or liquid pharmaceutical carrier or diluent.

3-tert.butylamino-2-(3,4-dihydroxyphenyl)propanol has particularly interesting properties.

The compounds of Formula I may be administered in pharmaceutically acceptable acid addition salt form. Such salts possess the same order of activity as the free bases and are readily prepared in conventional manner. Suitable such salt forms include organic acid salts such as the fumarate, maleate, tartrate, methane-, ethane- and benzenesulphonate, citrate and malate, and mineral acid

salts such as the hydrochloride, hydrobromide and sulphate.

The compounds of Formula I or their pharmaceutical-
ly acceptable acid addition salts may be used as medi-
caments on their own or in the form of appropriate
medicinal preparations, e.g. tablets, dragées, capsules,
granules, suppositories or injectable solutions or suspen-
sions, for enteral or parenteral administration. Aside from
the usual inorganic or organic pharmaceutically accept-
able adjuvants, e.g. lactose, starch, talc, stearic acid,
water, alcohols, natural or hardened oils and waxes, these
preparations may also contain suitable preserving stabiliz-
ing or wetting agents, solubilizers, sweetening or color-
ing substances and flavorings.

The invention accordingly also provides a phar-
maceutical composition comprising as active agent a com-
pound of Formula I or a pharmaceutically acceptable
acid addition salt thereof, in association with a phar-
maceutical carrier or diluent.

In the following non-limitative examples all tempera-
tures are indicated in degrees centigrade and are uncor-
rected.

EXAMPLE 1

2-(3,4-dihydroxyphenyl)-3-(isopropylamino)propanol [process variant (a)]

20 g. of 2-(3,4-dimethoxyphenyl)-3-isopropylamino-
propanol are dissolved in 250 cc. of methylene chloride
and cooled to -75° . 45 g. of boron tribromide in the
form of a 1 molar solution in methylene chloride are
slowly added dropwise while stirring at such a rate
that the temperature does not exceed 70° . After 5 hours
the solvent is distilled off in a vacuum, the residue is
heated under reflux for 1 hour with 100 cc. of ethanol,
the reaction solution is concentrated by evaporation and
the residue is recrystallized from ethanol/ether. The hy-
drobromide of the title compound has a M.P. of $87-91^{\circ}$.

The 2 - (3,4-dimethoxyphenyl)-3-(isopropylamino)pro-
panol, required as starting material, may be produced as
follows:

(a) A solution of 472 g. of 3,4-dimethoxytropic acid
ethyl ester in 200 cc. of ethanol is added dropwise to a
solution of 140 g. of isopropylamine in 200 cc. of ethanol
at room temperature while stirring. The reaction solu-
tion is subsequently heated to 50° for 3 hours, is filtered
and the filtrate is concentrated by evaporation in a
vacuum. The residue is taken up in chloroform and extracted
with 2 N hydrochloric acid. The hydrochloric acid solu-
tion is rendered alkaline with concentrated ammonia while
cooling, whereby crude 2-(3,4-dimethoxyphenyl)-3-(iso-
propylamino)propionic acid ethyl ester separates as a
yellow oil, and this is taken up in chloroform. The solu-
tion is dried over sodium sulphate and concentrated by
evaporation; the residue is converted into the hydrochlo-
ride with hydrochloric acid in ethanol. M.P. $159-162^{\circ}$.

(b) 96 g. of 2-(3-dimethoxyphenyl)-3-(isopropylami-
no)propionic acid ethyl ester are reduced in 1000
cc. of ether with 11.4 g. of lithium aluminium hydride by
heating under reflux for two hours. After decomposing
with a small amount of water, filtration is effected, the
ether solution is dried and concentrated by evaporation,
and 2-(3,4-dimethoxyphenyl) - 3 - (isopropylamino)pro-
panol is crystallized. M.P. $59-61^{\circ}$; the hydrochloride has
a M.P. of $150-152^{\circ}$.

EXAMPLE 2

3-tert.-butylamino-2-(3,4-dihydroxy- phenyl)propanol

3-tert.-butylamino-2-(3,4 - dimethoxyphenyl)-propanol
(obtained in a manner analogous to Example 1, M.P.
 $71-73^{\circ}$) is reacted in accordance with the process described
in Example 1. The hydrobromide of the title compound
has a M.P. of $113-115^{\circ}$.

EXAMPLE 3

3-sec.butylamino-2-(3,4-dihydroxy- phenyl)propanol

5 3-sec.butylamino-2-(3,4-dimethoxyphenyl)propanol ob-
tained in a manner analogous to Example 1, oil) is re-
acted in accordance with the process described in Exam-
ple 1. The hydrobromide of the title compound has a
M.P. of $85-89^{\circ}$.

EXAMPLE 4

3-butylamino-2-(3,4-dihydroxyphenyl)propanol

15 3-butylamino-2-(3,4 - dimethoxyphenyl)propanol (ob-
tained in a manner analogous to Example 1, M.P. $70-72^{\circ}$) is reacted in accordance with the process described
in Example 1. The hydrobromide of the title compound
has a M.P. of $93-95^{\circ}$.

EXAMPLE 5

3-cyclohexylamino-2-(3,4-dihydroxy- phenyl)propanol

20 3-cyclohexylamino-2-(3,4 - dimethoxyphenyl)propanol
(obtained in a manner analogous to Example 1, oil) is
reacted in accordance with the process described in Ex-
ample 1. The hydrobromide of the title compound has a
M.P. of $95-97^{\circ}$.

EXAMPLE 6

3-cyclopentylamino-2-(3,4-dihydroxy- phenyl)propanol

25 3-cyclopentylamino-2-(3,4 - dimethoxyphenyl)propanol
(obtained in a manner analogous to Example 1, M.P. of
the bis-naphthalene - 1,5-disulphonate $231-235^{\circ}$) is re-
acted in accordance with the process described in Exam-
ple 1. The hydrobromide of the title compound has a
M.P. of $92-95^{\circ}$.

EXAMPLE 7

3-cyclopropylamino-2-(3,4-dihydroxy- phenyl)propanol

30 3-cyclopropylamino-2-(3,4 - dimethoxyphenyl)propanol
(obtained in a manner analogous to Example 1, M.P. of
the hydrochloride $132-134^{\circ}$) is reacted in accordance
with the process described in Example 1. The hydrobro-
mide of the title compound has a M.P. of $56-60^{\circ}$.

EXAMPLE 8

2-(3,4-dihydroxyphenyl)-3-(3-phenyl- propylamino)propanol

35 2-(3,4-dimethoxyphenyl) - 3 - (3-phenylpropylamino)
propanol (obtained in a manner analogous to Example
1, M.P. of the hydrochloride $111-114^{\circ}$) is reacted in
accordance with the process described in Example 1.
55 The hydrobromide of the title compound has a M.P. of
 $108-110^{\circ}$.

EXAMPLE 9

2-(3,4-dihydroxyphenyl)-3-(1-phenyl- 2-propylamino)propanol

40 2-(3,4-dimethoxyphenyl)-3-(1-phenyl - 2 - propylami-
no)propanol (obtained in a manner analogous to Ex-
ample 1, M.P. of the bis-naphthalene-1,5-disulphonate
 $76-80^{\circ}$, decomp.) is reacted in accordance with the proc-
ess described in Example 1. The hydrobromide of the title
compound has a M.P. of $109-110^{\circ}$.

EXAMPLE 10

2-(3,4-dihydroxyphenyl)-3-(3,3-diphenyl- propylamino)propanol

45 2-(3,4 - dimethoxyphenyl)-3-(3,3 - diphenylpropylami-
no)propanol (obtained in a manner analogous to Exam-
ple 1, M.P. $117-119^{\circ}$) is reacted in accordance with the
process described in Example 1. The hydrobromide of the
title compound has a M.P. of $98-102^{\circ}$.

EXAMPLE 11

3-amino-2-(3,4-dihydroxyphenyl)propanol

20 g. of 3-amino - 2 - (3,4 - dimethoxyphenyl)propanol are dissolved in 250 cc. of methylene chloride and 52.5 g. of boron tribromide in the form of a 1 molar solution in methylene chloride are slowly added at -75° while stirring. After 5 hours the solvent is distilled off in a vacuum, the residue is heated under reflux with 100 cc. of ethanol for 1 hour, the reaction solution is concentrated by evaporation and the residue is recrystallized from ethanol/ether. The hydrobromide of the title compound has a M.P. of 87-91°.

The 3-amino - 2 - (3,4-dimethoxyphenyl)propanol, required as starting material, may be obtained as follows:

13 g. of concentrated sulphuric acid are added dropwise to a suspension of 10.7 g. of lithium aluminium hydride in 500 cc. of tetrahydrofuran while stirring and cooling with ice. The mixture is stirred for a further 15 minutes and a solution of 25 g. of 3,4-dimethoxy-phenylcyanoacetic acid ethyl ester in 50 cc. of tetrahydrofuran is added dropwise at 20°. The reaction mixture is subsequently stirred at 50° for a further 3 hours, the residual lithium aluminium hydride is then destroyed with a 10% caustic soda solution, filtration is effected, the tetrahydrofuran solution is dried over potassium carbonate and the solvent is distilled off. The resulting oil is converted into the hydrochloride and recrystallized from ethanol/ether. The hydrochloride has a M.P. of 204-206°.

EXAMPLE 12

2-(3,4-dihydroxyphenyl)-3-(n-propylamino)propanol

2-(3,4 - dimethoxyphenyl) - 3 - (n-propylamino)propanol (obtained in a manner analogous to Example 1, M.P. 72-74°) is reacted in accordance with the process described in Example 1. The hydrobromide of the title compound has a M.P. of 84-85°.

EXAMPLE 13

2-(3,4-dihydroxyphenyl)-3-(4-methyl-2-pentylamino)propanol

2-(3,4 - dimethoxyphenyl) - 3 - (4-methyl-2-pentylamino)propanol (obtained in a manner analogous to Example 1, M.P. of the hydrochloride 125-127°) is reacted in accordance with the process described in Example 1. The hydrobromide of the title compound has a M.P. of 145-147°.

EXAMPLE 14

2-(3,4-dihydroxyphenyl)-3-(phenethylamino)propanol

2-(3,4 - dimethoxyphenyl) - 3 - (phenethylamino)propanol (obtained in a manner analogous to Example 1, M.P. of the hydrochloride 149-151°) is reacted in accordance with the process described in Example 1. The hydrobromide of the title compound has a M.P. of 65-70°.

EXAMPLE 15

2-(3,4-dihydroxyphenyl)-3-(n-pentylamino)propanol

2-(3,4 - dimethoxyphenyl) - 3 - n-pentylamino)propanol (obtained in a manner analogous to Example 1, M.P. of the hydrochloride 133-136°) is reacted in accordance with the process described in Example 1. The hydrobromide of the title compound has a M.P. of 139-141°.

EXAMPLE 16

3-(n-hexylamino)-2-(3,4-dihydroxyphenyl)propanol

3-(n-hexylamino) - 2 - (3,4-dimethoxyphenyl)propanol (obtained in a manner analogous to Example 1, M.P. of the hydrochloride 94-97°) is reacted in accordance with the process described in Example 1. The hydrobromide of the title compound has a M.P. of 92-95°.

EXAMPLE 17

3-(n-heptylamino)-2-(3,4-dihydroxyphenyl)propanol

5 3-(n-heptylamino) - 2 - (3,4-dimethoxyphenyl)propanol (obtained in a manner analogous to Example 1, oil) is reacted in accordance with the process described in Example 1. The hydrobromide of the title compound has a M.P. of 128-131°.

EXAMPLE 18

2-(3,4-dihydroxyphenyl)-3-(4-phenylbutylamino)propanol

10 2-(3,4-dimethoxyphenyl) - 3 - (4 - phenylbutylamino)propanol (obtained in a manner analogous to Example 1, M.P. of the hydrochloride 116-118°) is reacted in accordance with the process described in Example 1. The hydrobromide of the title compound has a M.P. of 115-117°.

EXAMPLE 19

3-(p-hydroxyphenethylamino)-2-(3,4-dihydroxyphenyl)propanol

15 25 3-(p-methoxyphenethylamino) - 2 - (3,4 - dimethoxyphenyl)propanol (obtained in a manner analogous to Example 1, M.P. of the hydrochloride 144-146°) is reacted in accordance with the process described in Example 1. The hydrobromide of the title compound has a M.P. of 65-70°.

EXAMPLE 20

2-(3,4-dihydroxyphenyl)-3-[3-(p-hydroxyphenyl)propylamino]propanol

20 35 2-(3,4-dimethoxyphenyl)-3 - [3 - (p - methoxyphenyl)propylamino]propanol (obtained in a manner analogous to Example 1, M.P. 64-67°, M.P. of the hydrochloride 104-106°) is reacted in accordance with the process described in Example 1. The hydrobromide of the title compound has a M.P. of 165-168°.

EXAMPLE 21

2-(3,4-dihydroxyphenyl)-3-(1-phenyl-3-butylamino)propanol

40 45 2-(3,4-dimethoxyphenyl)-3-(1-phenyl - 3 - butylamino)propanol (obtained in a manner analogous to Example 1, M.P. of the hydrochloride 118-120°) is reacted in accordance with the process described in Example 1. The hydrobromide of the title compound has a M.P. of 90-94°.

EXAMPLE 22

3-ethylamino-2-(3,4-dihydroxyphenyl)propanol

50 55 3-ethylamino-2-(3,4 - dimethoxyphenyl)propanol (obtained in a manner analogous to Example 1, M.P. 67-69°) is reacted in accordance with the process described in Example 1. The hydrobromide of the title compound has a M.P. of 93-95°.

EXAMPLE 23

3-(4-hydroxybenzylamino)-2-(3,4-dihydroxyphenyl)propanol

60 65 3-(4-methoxybenzylamino)-2-(3,4 - dimethoxyphenyl)propanol (obtained in a manner analogous to Example 1, M.P. 70-72°, M.P. of the hydrochloride 147-149°) is reacted in accordance with the process described in Example 1. The hydrobromide of the title compound has a M.P. of 105-109°.

EXAMPLE 24

3-(3,4-dihydroxyphenethylamino)-2-(3,4-dihydroxyphenyl)propanol

70 75 3-(3,4-dimethoxyphenethylamino)-2-(3,4 - dimethoxyphenyl)propanol (obtained in a manner analogous to Example 1, M.P. of the hydrogen fumarate 65-67°) is reacted in accordance with the process described in Example

1. The hydrobromide of the title compound has a M.P. of 77-80°.

EXAMPLE 25

2-(3,4-dihydroxyphenyl)-3-(2,2-diphenylethylamino) propanol

2-(3,4-dimethoxyphenyl)-3-(2,2-diphenylethylamino) propanol (obtained in a manner analogous to Example 1, M.P. of the hydrochloride 182-184°) is reacted in accordance with the process described in Example 1. The hydrobromide of the title compound has a M.P. of 115-117°.

EXAMPLE 26

(+)-3-tert.butylamino-2-(3,4-dihydroxyphenyl)propanol hydrobromide

(+)-3-tert.butylamino-2-(3,4-dimethoxyphenyl)propanol is reacted in accordance with the process described in Example 1. The title compound has a M.P. of 102-104°, $[\alpha]_D^{20} = +31.5^\circ$ in ethanol.

EXAMPLE 27

(-)-3-tert.butylamino-2-(3,4-dihydroxyphenyl)propanol hydrobromide

(-)-3-tert.butylamino-2-(3,4-dimethoxyphenyl)propanol is reacted in accordance with the process described in Example 1. The title compound has a M.P. of 107-109°, $[\alpha]_D^{20} = -32.1^\circ$ in ethanol.

The starting materials for Examples 26 and 27, i.e. (+)- or (-)-3-tert.butylamino-2-(3,4-dimethoxyphenyl)propanol, are obtained as follows:

(a) A solution of 472 g. of 3,4-dimethoxyatropic acid ethyl ester in 200 cc. of ethanol is added dropwise to a solution of 175 g. of tert.butylamine in 200 cc. of ethanol at room temperature while stirring. The reaction mixture is subsequently heated to 50° for 3 hours, filtration is effected and the filtrate is concentrated by evaporation in a vacuum. The residue is taken up in chloroform and extracted with 2 N hydrochloric acid. The hydrochloric acid solution is rendered alkaline with concentrated ammonia while cooling, whereby a yellow oil separates, which is taken up in chloroform. The solution is dried over sodium sulphate and concentrated by evaporation. The residue, i.e. 3-tert.butylamino-2-(3,4-dimethoxyphenyl)propionic acid ethyl ester, is converted into the hydrochloride with hydrochloric acid in ethanol.

(b) 105 g. of 3-tert.butylamino-2-(3,4-dimethoxyphenyl)propionic acid ethyl ester are reduced in 1000 cc. of ether with 11.4 g. of lithium aluminium hydride by heating under reflux for two hours. After decomposing with a small amount of water, filtration is effected, the ether solution is dried and concentrated by evaporation, and the residue, the racemate form of 3-tert.butylamino-2-(3,4-dimethoxyphenyl)propanol, is crystallized. The racemate has a M.P. of 71-73°.

(c) 40 g. of racemic 3-tert.butylamino-2-(3,4-dimethoxyphenyl)propanol are dissolved in 4 liters of ethanol and a solution of 60 g. of (-)-di-O-(p-toluoyl)-L-tartaric acid in 4 liters of ethanol is added. (+)-3-tert.butylamino-2-(3,4-dimethoxyphenyl)propanol hydrogen-(-)-di-O-(p-toluoyl)-L-tartrate crystallizes. M.P. after recrystallization from methanol 191-192°.

The salt of the optically active base is decomposed with 2 N caustic soda solution/chloroform; the base resulting from the chloroform phase is recrystallized from cyclohexane. (+)-3-tert.butylamino-2-(3,4-dimethoxyphenyl)propanol is obtained. M.P. 70-71°, $[\alpha]_D^{20} = +31.90$ in ethanol.

(d) The ethanolic mother liquor obtained in (c) above is concentrated by evaporation, the resulting salt mixture is decomposed with 2 N caustic soda solution, the liberated base is taken up in chloroform, the solution is dried over sodium sulphate, the chloroform is distilled off and the resulting base is dissolved in 2.5 liters of ethanol. A solu-

tion of 40 g. of (+)-di-O-(p-toluoyl)-D-tartaric acid in 2.5 liters of ethanol is added to this solution. (-)-3-tert.butylamino-2-(3,4-dimethoxyphenyl)propanol hydrogen-(-)-di-O-(p-toluoyl)-D-tartrate crystallizes. M.P. after recrystallization from methanol 191-192°.

The salt of the optically active base is decomposed with 2 N caustic soda solution/chloroform. The base resulting from the chloroform phase is recrystallized from cyclohexane. (-)-3-tert.butylamino-2-(3,4-dimethoxyphenyl)propanol is obtained. M.P. 77-79°, $[\alpha]_D^{20} = -32.5^\circ$ in ethanol.

EXAMPLE 28

3-tert.butylamino-2-(3,4-dihydroxyphenyl)propanol

10.0 g. of racemic 3-tert.butylamino-2-(3,4-dimethoxyphenyl)propanol (prepared as described in Example 27) are heated under reflux in 100 cc. of 48% hydrobromic acid for 15 minutes. The reaction solution is subsequently evaporated to dryness and the residue is recrystallized from ethanol/ether.

The hydrobromide of the title compound has a M.P. of 113-115°.

EXAMPLE 29

2(3,4-dihydroxyphenyl)-3-(p-methoxyphenethylamino) propanol [process variant (b)]

11.0 g. of 2-(3,4-dibenzoyloxyphenyl)-3-(p-methoxyphenethylamino)propanol are dissolved in 200 cc. of ethanol, 1.0 g. of palladium on charcoal (10%) is added and hydrogenation is effected at room temperature for 30 minutes. The catalyst is then filtered off, the solution is concentrated by evaporation and the residue is converted into the hydrochloride of the title compound. M.P. 198-200°.

The starting material is obtained as follows:

(a) 7.6 g. of sodium are dissolved in 200 cc. of ethanol, the solution is evaporated to dryness in the absence of moisture and the residue is suspended in 200 cc. of absolute toluene. 80 g. of oxalic acid diethyl ester are added dropwise and subsequently 123 g. of 3,4-dibenzoyloxyphenylacetic acid ethyl ester are added dropwise at 35-40° while stirring. The mixture is heated under reflux while stirring for 2 hours, is then cooled to -45° and 85 cc. of 4 N sulphuric acid are added. 40 g. of 36% formalin and 90 cc. of a saturated potassium carbonate solution are added over a period of 3 hours. The reaction mixture is stirred at room temperature over night, is then diluted with 250 cc. of water and the toluene phase is separated. After drying over sodium sulphate the solvent is distilled off, and the resulting α -(3,4-dibenzoyloxyphenyl)acrylic acid ethyl ester is used for the next reaction without previous purification.

(b) 38.8 g. of α -(3,4-dibenzoyloxyphenyl)acrylic acid ethyl ester and 14 g. of p-methoxyphenethylamine are heated under reflux in 100 cc. of ethanol for 10 hours. After distilling off the ethanol, the residue is dissolved in 300 cc. of ether and the solution is shaken with 25 cc. of 4 N hydrochloric acid, whereby the hydrochloride of 2-(3,4-dibenzoyloxyphenyl)-3-p-methoxyphenethylaminopropionic acid ethyl ester crystallizes. M.P. 85-88° after recrystallization from ethanol/ether.

(c) 16.7 g. of 2-(3,4-dibenzoyloxyphenyl)-3-p-methoxyphenethylaminopropionic acid ethyl ester are reduced in 200 cc. of tetrahydrofuran with 2.0 g. of lithium aluminium hydride. The reaction is complete after heating under reflux for 2 hours. After decomposing the excess reducing agent with a small amount of water, filtration is effected and the tetrahydrofuran solution is dried over sodium sulphate and the solvent is distilled off. The resulting 2-(3,4-dibenzoyloxyphenyl)-3-(p-methoxyphenethylamino)propanol is recrystallized from ethyl acetate/petroleum ether. M.P. 81-82°.

13
EXAMPLE 30

2-(3,4-dihydroxyphenyl)-3-(isopropylamino)propanol
[process variant (c)]

5.0 g. of 3-amino-2-(3,4 - dihydroxyphenyl)propanol hydrobromide (prepared as in Example 11) are dissolved in 30 cc. of ethanol, 20 cc. of acetone, 3 cc. of glacial acetic acid and 0.5 g. of palladium on charcoal are added, and hydrogenation is effected at 40° and a hydrogen pressure of 6 atmospheres for about 10 hours. After cooling the catalyst is filtered off, the solution is evaporated in a 10 vacuum and the residue is recrystallized from ethanol/ether. The hydrobromide of the title compound has a M.P. of 87-91°.

EXAMPLE 31

3-n-butylamino-2-(3,4-dihydroxyphenyl)propanol

5.0 of 3 - amino-2-(3,4 - dihydroxyphenyl)propanol hydrobromide are reacted with butyraldehyde in analogous manner to Example 30. The hydrobromide of the title compound has a M.P. of 93-95°.

EXAMPLE 32

3-sec.butylamino-2-(3,4-dihydroxyphenyl)propanol

3-amino-2-(3,4 - dihydroxyphenyl)propanol is reacted with methyl ethyl ketone in accordance with the process described in Example 30. The hydrobromide of the title compound has a M.P. of 85-89°.

EXAMPLE 33

3-cyclohexylamino-2-(3,4-dihydroxyphenyl)propanol

3-amino-2-(3,4-dihydroxyphenyl)propanol is reacted with cyclohexanone in accordance with the process described in Example 30. The hydrobromide of the title compound has a M.P. of 95-97°.

EXAMPLE 34

3-cyclopentylamino-2-(3,4-dihydroxyphenyl)propanol

3-amino-2-(3,4-dihydroxyphenyl)propanol is reacted 40 with cyclopentanone in accordance with the process described in Example 30. The hydrobromide of the title compound has a M.P. of 92-95°.

EXAMPLE 35

2-(3,4-dihydroxyphenyl)-3-(3-phenylpropylamino)propanol

3-amino-2-(3,4-dihydroxyphenyl)propanol is reacted with 3-phenylpropionaldehyde in accordance with the process described in Example 30. The hydrobromide of the title compound has a M.P. of 108-110°.

EXAMPLE 36

2-(3,4-dihydroxyphenyl)-3-(1-phenyl-2-propylamino)propanol

3-amino-2-(3,4-dihydroxyphenyl)propanol is reacted with benzyl methyl ketone in accordance with the process described in Example 30. The hydrobromide of the title compound has a M.P. of 109-110°.

EXAMPLE 37

2-(3,4-dihydroxyphenyl)-3-(3,3-diphenylpropylamino)propanol

3-amino-2-(3,4-dihydroxyphenyl)propanol is reacted with 3,3-diphenylpropionaldehyde in accordance with the process described in Example 30. The hydrobromide of the title compound has a M.P. of 98-102°.

EXAMPLE 38

2-(3,4-dihydroxyphenyl)-3-(n-propylamino)propanol

3-amino-2-(3,4-dihydroxyphenyl)propanol is reacted with propionaldehyde in accordance with the process described in Example 30. The hydrobromide of the title compound has a M.P. of 84-85°.

14
EXAMPLE 39

2-(3,4-dihydroxyphenyl)-3-(4-methyl-2-pentylamino)propanol

5 3-amino-2-(3,4-dihydroxyphenyl)propanol is reacted with 4-methyl-2-pentanone in accordance with the process described in Example 30. The hydrobromide of the title compound has a M.P. of 145-147°.

EXAMPLE 40

2-(3,4-dihydroxyphenyl)-3-(phenethylamino)propanol

3-amino-2-(3,4-dihydroxyphenyl)propanol is reacted 15 with phenylacetaldehyde in accordance with the process described in Example 30. The hydrobromide of the title compound has a M.P. of 65-70°.

EXAMPLE 41

2-(3,4-dihydroxyphenyl)-3-(n-pentylamino)propanol

20 3-amino-2-(3,4-dihydroxyphenyl)propanol is reacted with valeraldehyde in accordance with the process described in Example 30. The hydrobromide of the title compound has a M.P. of 139-141°.

EXAMPLE 42

3-(n-hexylamino)-2-(3,4-dihydroxyphenyl)propanol

3-amino-2-(3,4-dihydroxyphenyl)propanol is reacted 25 with hexanal in accordance with the process described in Example 30. The hydrobromide of the title compound has a M.P. of 92-95°.

EXAMPLE 43

3-(n-heptylamino)-2-(3,4-dihydroxyphenyl)propanol

35 3-amino-2-(3,4-dihydroxyphenyl)propanol is reacted with n-heptanal in accordance with the process described in Example 30. The hydrobromide of the title compound has a M.P. of 128-131°.

EXAMPLE 44

2-(3,4-dihydroxyphenyl)-3-(4-phenylbutylamino)propanol

40 3-amino-2-(3,4-dihydroxyphenyl)propanol is reacted with 4-phenylbutyraldehyde in accordance with the process described in Example 30. The hydrobromide of the title compound has a M.P. of 115-117°.

EXAMPLE 45

3-(p-hydroxyphenethylamino)-2-(3,4-dihydroxyphenyl)propanol

45 3-amino-2-(3,4-dihydroxyphenyl)propanol is reacted with p-hydroxy-phenylacetaldehyde in accordance with the process described in Example 30. The hydrobromide of the title compound has a M.P. of 65-70°.

EXAMPLE 46

2-(3,4-dihydroxyphenyl)-3-[3-(p-hydroxyphenyl)propylamino]propanol

50 3-amino - 2 - (3,4-dihydroxyphenyl)propanol is reacted with 3-(p-hydroxyphenyl)propionaldehyde in accordance with the process described in Example 30. The hydrobromide of the title compound has a M.P. of 165-168°.

EXAMPLE 47

2-(3,4-dihydroxyphenyl)-3-(1-phenyl-3-butylamino)propanol

55 3-amino - 2 - (3,4-dihydroxyphenyl)propanol is reacted with 4-phenyl-2-butanone in accordance with the process described in Example 30. The hydrobromide of the title compound has a M.P. of 90-94°.

15
EXAMPLE 48

3-ethylamino-2-(3,4-dihydroxyphenyl)propanol

3-amino - 2 - (3,4-dihydroxyphenyl)propanol is reacted with acetaldehyde in accordance with the process described in Example 30. The hydrobromide of the title compound has a M.P. of 93-95°.

EXAMPLE 49

3-(3,4-dihydroxyphenethylamino)-2-(3,4-dihydroxyphenyl)propanol

3-amino - 2 - (3,4-dihydroxyphenyl)propanol is reacted with 3,4-dihydroxy-phenylacetaldehyde in accordance with the process described in Example 30. The hydrobromide of the title compound has a M.P. of 77-80°.

EXAMPLE 50

2-(3,4-dihydroxyphenyl)-3-(2,2-diphenylethylamino)propanol

3-amino - 2 - (3,4-dihydroxyphenyl)propanol is reacted with diphenylacetaldehyde in accordance with the process described in Example 30. The hydrobromide of the title compound has a M.P. of 115-117°.

EXAMPLE 51

2-(3,4-dihydroxyphenyl)-3-(p-methoxyphenethylamino)propanol

3-amino - 2 - (3,4-dihydroxyphenyl)propanol is reacted with p-methoxy-phenylacetaldehyde in accordance with the process described in Example 30. The hydrochloride of the title compound has a M.P. of 198-200°.

EXAMPLE 52

3-[(cyclopentylmethyl)amino]-2-(3,4-dihydroxyphenyl)propanol [process variant (a)]

20.0 g. of 3-[(cyclopentylmethyl)amino]-2-(3,4-dimethoxyphenyl)propanol are dissolved in 250 cc. of methylene chloride and 39 g. of boron tribromide, dissolved in 250 cc. of methylene chloride, are added dropwise thereto while maintaining the reaction temperature at -75°. The cooler is then removed, the reaction mixture is stirred at room temperature for 1 hour and the solvent is then distilled off. The residue is boiled under reflux with 100 cc. of ethanol for 1 hour. The solution is concentrated and ether is added until the reaction product crystallizes as hydrobromide. M.P. 87-91° (decomp.).

The starting material is obtained as follows:

(a) 52.0 g. of 3,4-dimethoxyatropic acid ethyl ester and 19.8 g. of cyclopentylmethylamine are heated to 60° with 20 cc. of ethanol for 3 hours. The reaction mixture is concentrated by evaporation in a vacuum, the oily residue is dissolved in chloroform and extraction is effected with 2 N hydrochloric acid. The hydrochloric acid solution is rendered alkaline with concentrated ammonia while cooling and is then extracted with chloroform. The chloroform extract is dried over sodium sulphate and concentrated by evaporation and the residue, i.e. 3-[(cyclopentylmethyl)amino]-2-(3,4-dimethoxyphenyl)propionic acid ethyl ester, is converted into the hydrochloride with hydrochloric acid in ethanol. M.P. 127-129°.

(b) 50 g. of 3-[(cyclopentylmethyl)amino]-2-(3,4-dimethoxyphenyl)propionic acid ethyl ester are reduced in 400 cc. of tetrahydrofuran with 6.5 g. of lithium aluminium hydride by heating for 2 hours. After decomposing the residual reducing agent with a small amount of water, filtration, drying and concentrating by evaporation are effected and 3-[(cyclopentylmethyl)amino]-2-(3,4-dimethoxyphenyl)propanol is crystallized from ethyl acetate/petroleum ether. M.P. 67-70°.

16
EXAMPLE 53

3,(3-cyclopentylpropylamino)-2-(3,4-dihydroxyphenyl)propanol

5 3 - (3 - cyclopentylpropylamino) - 2 - (3,4 - dimethoxyphenyl)propanol is reacted in accordance with the process described in Example 1. The hydrobromide of the title compound has a M.P. of 164-167°.

The starting materials are produced in a manner analogous to that described in Example 52:

10 (a) Reaction of 3,4-dimethoxyatropic acid ethyl ester with 3-cyclopentylpropylamine yields 3 - (3-cyclopentylpropylamino) - 2 - (3,4-dimethoxyphenyl)propionic acid ethyl ester, M.P. of the naphthalene - 1,5 - disulphonate 179-181°, and

15 (b) Reduction of the latter yields 3-(3-cyclopentylpropylamino)-2-(3,4-dimethoxyphenyl)propanol, M.P. of the hydrochloride 136-138°.

EXAMPLE 54

3-[(cyclohexylmethyl)amino]-2-(3,4-dihydroxyphenyl)propanol

20 3-[(cyclohexylmethyl)amino]-2-(3,4-dimethoxyphenyl)propanol is reacted in accordance with the process described in Example 1. The hydrobromide of the title compound has a M.P. of 112-115°.

The starting materials are produced in a manner analogous to that described in Example 52:

25 (a) Reaction of 3,4-dimethoxyatropic acid ethyl ester with cyclohexylmethylamine yields 3 - [(cyclohexylmethyl)amino] - 2 - (3,4-dimethoxyphenyl)propionic acid ethyl ester, M.P. of the hydrochloride 130-133°, and

30 (b) Reduction of the latter yields 3-[(cyclohexylmethyl)amino] - 2 - (3,4-dimethoxyphenyl)propanol, M.P. 130-132°.

EXAMPLE 55

3-[(cyclopentylmethyl)amino]-2-(3,4-dihydroxyphenyl)propanol

35 3 - amino - 2-(3,4-dihydroxyphenyl)propanol is reacted with cyclopentylformaldehyde in accordance with the process described in Example 30. The hydrobromide of the title compound has a M.P. of 87-91° (decomp.).

EXAMPLE 56

3-[(3-cyclopentylpropylamino)-2-(3,4-dihydroxyphenyl)propanol

40 3-amino - 2 - (3,4-dihydroxyphenyl)propanol is reacted with 3 - cyclopentylpropanone in accordance with the process described in Example 30. The hydrobromide of the title compound has a M.P. of 164-167°.

EXAMPLE 57

3-[(cyclohexylmethyl)amino]-2-(3,4-dihydroxyphenyl)propanol

45 3 - amino - 2 - (3,4-dihydroxyphenyl)propanol is reacted with cyclohexylformaldehyde in accordance with the process described in Example 30. The hydrobromide of the title compound has a M.P. of 112-115°.

What is claimed is:

1. A compound of the formula:

wherein

R_1 is alkyl of 1 to 8 carbon atoms,

or a pharmaceutically acceptable acid addition salt thereof.

2. The compound of claim 1, which is 2-(3,4-dihydroxyphenyl) - 3 - (isopropylamino)propanol.

3. The compound of claim 1, which is 3-tert. butylamino-2-(3,4-dihydroxyphenyl)propanol.

4. The compound of claim 1, which is 3-sec. butylamino-2-(3,4-dihydroxyphenyl)propanol.
5. The compound of claim 1, which is 3-butylamino-2-(3,4-dihydroxyphenyl)propanol.
6. The compound of claim 1, which is 2-(3,4-dihydroxyphenyl)-3-(n-propylamino)propanol. 5
7. The compound of claim 1, which is 2-(3,4-dihydroxyphenyl)-3-(4-methyl-2-pentylamino)propanol.
8. The compound of claim 1, which is 2-(3,4-dihydroxyphenyl)-3-(n-pentylamino)propanol.
9. The compound of claim 1, which is 3-(n-hexylamino)-2-(3,4-dihydroxyphenyl)propanol.
10. The compound of claim 1, which is 3-(n-heptylamino)-2-(3,4-dihydroxyphenyl)propanol.
11. The compound of claim 1, which is 3-ethylamino-2-(3,4-dihydroxyphenyl)propanol.

12. The compound of claim 1, which is (+) - 3-tert.-butylamino - 2-(3,4-dihydroxyphenyl)proanol hydrobromide.

13. The compound of claim 1, which is (-) - 3 - tert.-butylamino - 2 - (3,4-dihydroxyphenyl)proanol hydrobromide.
